I. F. WIELGOSZ,
AEROPLANE STARTING AND LANDING PLATFORM,
APPLICATION FILED FEB. 4, 1920.

1,345,335.

Patented June 29, 1920.

INVENTOR.

BY Ignatz F. Wielgoosz
George C. Henricke

ATTORNEY.

UNITED STATES PATENT OFFICE.

IGNATZ F. WIELGOSZ, OF MILWAUKEE, WISCONSIN.

AEROPLANE STARTING AND LANDING PLATFORM.

1,345,335.

Specification of Letters Patent. Patented June 29, 1920.

Application filed February 4, 1920. Serial No. 356,216.

To all whom it may concern:

Be it known that I, IGNATZ F. WIELGOSZ, a citizen of the United States, residing at Milwaukee, county of Milwaukee, and State of Wisconsin, have invented certain new and useful Improvements in Aeroplane Starting and Landing Platforms, of which the following is a specification.

This invention relates to a launching and landing apparatus for aeroplanes which may be used in aviation fields, or on the decks of battleships or ships generally; or on the roofs of buildings or otherwise as may be desirable.

The invention has for an object to provide a simple and easily constructed form of apparatus by which an aeroplane can be caused to rise in the air without an initial run along the ground, or quickly caused to halt upon alighting.

For further comprehension of the invention, and of the objects and advantages thereof, reference will be had to the following description and accompanying drawings, and to the appended claims in which the various novel features of the invention are more particularly set forth.

Figure 1 of the drawings is a plan view of an aeroplane launching and landing apparatus constructed according to my invention.

Fig. 2 is a side elevation thereof.

Fig. 3 is a transverse section on the line 3—3 of Fig. 1.

As here shown my improved aeroplane launching and landing apparatus comprises an endless band or conveyer indicated generally at 10 and which may be of the general type employed commonly in treadmills comprising the cross strips 11 secured at opposite ends to the endless ropes 12, this endless band 10 being looped over suitable pairs of wheels, comprising a front pair 13 and a rear pair 14, the band extending in a general horizontal direction.

The wheels 13 and 14 are fixed on a pair of shafts 15 and 16 mounted at opposite ends in pillow blocks 17 and 18 adapted to be fixed to a suitable base not shown. The pillow blocks are provided with guideways 19 and 20, the guideways of the respective pairs of pillow blocks facing toward one another as shown. Bearing blocks 21 and 22 are slidably mounted in these guideways and have the ends of the shafts 15 and 16 respectively journaled therein, these bearing

blocks being held in position by the tongue and groove connections 23.

Fixed each at one end to the bearings 21 and 22 respectively are rigid rods 24 and 25 which extend toward one another the two rods on each side of the apparatus being in alinement as will be understood. These rods have their adjacent ends oppositely screw threaded as at 26 and 27, these screw threaded ends engaging in a turnbuckle 28 provided with a handwheel 29. It will be obvious that with this arrangement the requisite tension can be placed on the endless band 10, rotation of the turnbuckle in opposite directions drawing the shafts nearer to one another or spacing them farther apart.

Fixed upon one end of shaft 16 is a pulley 31 which is connected by a belt 32 with a second pulley 33 on the shaft of an electric motor 34 which is controlled by a rheostat 35 provided with suitable reversing means, rotation of the motor, as will be obvious imparting movement to the band 10.

By means of the speed control device the device may be given an even increase in speed when the aeroplane is launched therefrom, while the device is operated to travel reversely to the aeroplane when descending and the speed thereof evenly diminished as the aeroplane comes to rest, the latter having if desired suitable skids to engage the device when it descends thereon.

A runway of any suitable construction as for instance indicated in Figs. 1 and 2 of the drawing is provided on both ends of the device for receiving the impact of a landing plane.

Having thus described my invention what I claim as new and desire to secure by Letters Patent of the United States is as follows—

1. An aeroplane launching and landing apparatus comprising an endless band, means for causing same band to move at various speeds, said means comprising an electric motor and a rheostat for controlling said motor, sprocket wheels over which said band is looped, shafts on which said sprocket wheels are mounted, bearing blocks in which said shafts are journaled, pillow blocks formed with guides in which said bearing blocks are slidably mounted, rods projecting rigidly from said pillow blocks toward one another and having adjacent ends oppositely screw threaded and turnbuckles engaging said oppositely screw threaded ends,

2. An aeroplane launching and landing apparatus comprising an endless band, sprocket wheels over which said band is looped, shafts on which said sprocket wheels are mounted, bearing blocks in which said shafts are journaled, pillow blocks formed with guides in which said bearing blocks are slidably mounted, rods projecting rigidly from said pillow blocks toward one another and having adjacent ends oppositely screw threaded and turnbuckles engaging said oppositely screw threaded ends.
- 5 In testimony whereof I have affixed my signature.

IGNATZ F. WIELGOSZ.
